UNITED STATES PATENT OFFICE

RICHARD LEE RODGERS, OF CHICAGO, ILLINOIS, ASSIGNOR, BY MESNE ASSIGNMENTS, TO CHARCOLITE CORPORATION, OF CLINTON, INDIANA, A CORPORATION OF INDIANA

APPARATUS FOR CARBONIZING COAL

Application filed February 27, 1922. Serial No. 539,361.

This invention relates to the carbonization or "coking" of coal consisting of solid carbonaceous material, and its object is to provide a method and apparatus whereby a uniform product of high quality may be produced in a simple, economical and efficient manner.

The invention contemplates subdividing the coal being coked into relatively small parts, and immersing these relatively small charges, in a suitable container, in a bath of molten material, such as fused salts. By this means the temperature is under perfect control, is uniformly applied to the charge, and the heat is transmitted to the charge directly and in an efficient and economical manner. A heat storing reservoir is provided, equalizing the heat applied to the charge, at all points and throughout the operation.

20 The method of coking coal by placing the same in a heat conductive container immersed in a bath of fused salts is particularly efficacious in the production of low temperature coke.

25 In the drawings:

Fig. 1 is a perspective view of a carbonizing unit partly broken away,

Fig. 2 is a sectional elevation thereof,

Fig. 3 is a sectional elevation thereof on a 30 plane adjacent to that of Fig. 2,

Fig. 4 is a plan sectional view, and

Fig. 5 is an elevation partly in section on a line at right angles to the line of the section in Figs. 2 and 3.

35 The method of this invention could be carried out in various forms of apparatus; I shall, however, describe herein an illustrative form.

The essential operating parts of the structure selected for illustrative purposes may be seen in Fig. 1, wherein is shown a vat 1, containing the molten material comprising the bath. The front and rear sides 2 of the vat 1 are provided with opposite vertical slots extending nearly but not quite to the bottom. In these slots are mounted the chambers 3 to contain the charge. These chambers are substantially U-shaped in cross section and are provided with enlargements at 45 the front and rear thereof, in which enlarge-

ments are the exterior grooves 4 (which receive the edges of the walls defining the vertical slots in the front and rear wall 2 of the vat); and the interior grooves 5 into which the removable ends 6 of the chambers are slidably fitted. Thus each chamber, for coal, extends almost but not quite to the bottom of the tank or vat, opens through the front and rear sides of said tank or vat, as well as at the top. These chambers are supported on the saddles 7 resting on the bottom of the vat. They are provided with strengthening ribs 8, and with horizontal exterior flanges 9 near the top thereof upon which rest the plates 10, which cover the liquid filled compartments of the vat, between the chambers into which the coal is placed. The chambers 3 flare sideways at the top as shown at 11 and are provided with cross members 12 at frequent intervals. Between the members 12 the sectional covers 13, fit with a wedge fit. The whole exterior of the structure, except the ends of the chambers, is suitably insulated by insulation 14, shown in Figs. 4 and 5. Outlets 15 lead from the chambers to a gas manifold 16. In operation the charges of coal may be dumped from a travelling hopper into the chambers 3, (the covers 13 being removed), the covers 13 then replaced, and the coal coked. At the end of the coking operation by removing the ends 6 of the chambers the coke may be pushed out laterally by a plunger, or other mechanism well known in the art, after which the ends 6 are replaced and a new charge provided.

40 The coking chambers 3 are in this instance substantially eight inches wide, i. e. eight inches between the heated walls. The other dimensions may be varied almost at will. I have found that with a width of eight inches efficient low temperature coking is permitted.

The whole structure is mounted on a fire arch whose construction will now be described.

45 The fire chamber is shown at 20. It extends along an entire unit which contains many coking chambers, from the fire chamber the gases pass rearwardly through flues 21, then forwardly through flues 22, up through flues 23, and through the inter-

stices of brick work 24, which surrounds tank or vat adapted to contain fused salts, the fire boxes 20, and finally to the stack. By this arrangement efficient heating for the tank 1 is provided. Other arrangements of course could be substituted. Gas or liquid fuel may be used, and the temperature controlled by devices well-known in the art.

From the construction shown it will be apparent that while the coal is dumped or dropped vertically into the coking chambers, it can be removed therefrom horizontally. Thus at the end of the coking operation the ends 6 of the coking chambers 3 are raised, and by any suitable plunger mechanism (or by hand plunging) the coke may be pushed horizontally out of the chamber to a suitable dumping pit located alongside the unit.

Having described the apparatus, I shall cite as an illustrative embodiment of the invention the application to a container containing coal of a bath comprising a mixture of three parts of calcium chloride and one part of a sodium chloride. This fuses and may be maintained as a liquid at approximately 932° F. and may be heated from that point over a considerable range of temperature, and forms an excellent illustrative fused medium for the transfer of heat to the coal, uniformly and directly through the heat conductive walls of the coal chambers. In practice the temperature of the bath may be equalized if desired, by a circulatory action in it and the transfer of the heat to the coal is effected by direct conduction.

The liquid molten material, provides a "reservoir" of heat from which the heat flows uniformly to the entire surface of the coal chambers with which it contacts. This uniformity of application of the heat I regard as of great importance. Furthermore variations in the heat produced in the fire box, are effectively eliminated by the time the heat is transferred to the coal. In other words heat is delivered to a heat reservoir of large capacity, and will be delivered therefrom at a substantially uniform rate in spite of considerable fluctuation of temperature in the fire box.

The method and apparatus herein described is adapted for use with various forms of coal including solid carbonaceous products, such as lignite and similar solid mineral substances adapted to be treated by heat to drive off volatile material and leaving a carbonaceous residue, but is particularly adapted for coking bituminous coal.

Having described my invention, I claim:—

1. Apparatus for carbonizing coal comprising a liquid bath, means for heating said bath, a chamber in said bath opening above said bath and means permitting discharging the contents of said chamber laterally therefrom.

2. In apparatus of the class described, a

a plurality of chambers opening through the sides and at the top of said vat, said chambers being supported above the bottom of said vat whereby the fused salt may act upon the bottom of said chambers, removable closures for the top and sides of said chambers, whereby coal may be dropped into said chambers and coke laterally pushed out therefrom, and means for heating the vat.

In witness whereof, I hereunto subscribe my name this 15th day of February, A. D. 1922.

RICHARD LEE RODGERS.
